UNITED STATES PATENT OFFICE.

WILLIAM GRANT FISKE, OF PURFLEET, ENGLAND, ASSIGNOR TO THAMES PAPER COMPANY LIMITED, OF PURFLEET, ENGLAND.

MANUFACTURE OF BOXES AND SIMILAR RECEPTACLES.

1,216,791.

Specification of Letters Patent. Patented Feb. 20, 1917.

Application filed August 26, 1915. Serial No. 47,409.

To all whom it may concern:

Be it known that I, WILLIAM GRANT FISKE, a citizen of the United States of America, and resident of Purfleet, Essex, 5 England, have invented certain new and useful Improvements in the Manufacture of Boxes and Similar Receptacles, of which the following is a specification.

This invention relates to what is commonly known as a three-part box (or similar receptacle) that is a box formed of two rigid end-members, and a third member constituted by a sheet of cardboard or like material lapped about and nailed by its lateral 15 margins to the edges of the respective end-members.

In such boxes the efficiency of the connection between each end-member and the third member (particularly as regards resistance 20 to pressure tending to force the end-member outward or inward transversely of the nails, as well as resistance to bursting strains tending to strip the third member off the end-members in the direction of the length 25 of the nails) has usually been dependent upon the capability of those portions of the cardboard which immediately surround the nails to resist tearing; those portions of the cardboard which intervene between adjacent nail-holes bearing practically no share 30 in resisting the tendency to tear. Hence, as the nails are frequently spaced at somewhat wide intervals apart, the strength of such boxes with reference to strains of the 35 kind just referred to does not correspond with the capability of the box to withstand other strains to which it is liable to be subjected.

According to the present invention, the 40 material of the third member, between adjacent nail-holes, is caused to participate to an equal (or substantially equal) extent with the material immediately surrounding the holes in the work of resisting tearing 45 and other strains which tend to destroy the structure of the box by means of reinforcing material formed of pliable material (e. g. tough paper or fabric or layers of paper and fabric united by an agglutinant) 50 applied to the lateral margins of the cardboard forming the third member of the box and caused to adhere to said third member

by an agglutinant as to become virtually incorporated therewith.

In the accompanying drawings, Figure 1 55 is a perspective view showing an example of a three-part box embodying the present invention, and Fig. 2 is a perspective view, drawn to a larger scale, showing a portion of a sheet of cardboard with part of a reinforcing strip in process of application to the cardboard.

As shown in Fig. 1, the box comprises end-members each constituted by a flat wooden frame *a* and a sheet of cardboard 65 or equivalent relatively thin material *b*, a sheet *c* of cardboard or the like being lapped about the two end-members and secured by its lateral margins to the edges of the respective end-members by means of nails as 70 indicated at *d*.

e, *e* (Fig. 1) are two reinforcing strips, which are applied to the respective lateral margins of the third member *c* so as to be transfixed by the nails *d*. In the example 75 illustrated, the reinforcing strips *e* are formed of a layer *f* of paper backed externally by a layer *g* of canvas or other suitable fabric secured to the paper layer 80 by a suitable agglutinant.

In practice according to my invention the lower surface of each strip, before it is applied to the marginal edge of the third member *c*, is coated with an adhesive capable of causing the strip to adhere so strongly 85 to the cardboard *c* as to become incorporated therewith. The adhesive may either be applied to the strip immediately before the latter is affixed to the cardboard, or it may be applied beforehand (for example during 90 the manufacture of the strips in quantity), allowed to dry, and moistened or softened immediately before the strip is affixed to the member *c*.

Inasmuch as, in a strip formed of layers 95 of paper and fabric (as in Fig. 2), the paper would be less absorbent than the fabric, the under layer to which the adhesive for securing such a composite strip in position is applied should preferably be of paper.

I claim:

A receptacle comprising rigid end members, a cardboard member extending about the peripheries of said end members to form

the body of the receptacle, reinforcing means comprising individual strips of paper extending continuously along the marginal edges of said member and secured thereto by means of an adhesive so as to be carried by said member, and a layer of reinforcing fabric secured in surface engagement with

each of said strips of paper, and nails or the like passing through said fabric layers, paper strips and cardboard member and into 10 said end members whereby the cardboard member and end members are secured together to form the receptacle.

WILLIAM GRANT FISKE.

It is hereby certified that Letters Patent No. 1,216,791, granted February 20, 1917, upon the application of William Grant Fiske, of Purfleet, England, for an improvement in "The Manufacture of Boxes and Similar Receptacles," were erroneously issued to Thames Paper Company Limited, as owner of the entire interest in said invention, whereas said Letters Patent should have been issued to *the inventor, said Fiske and Thames Paper Company, jointly*, said company being assignee of *one-half* interest only, as shown by the records of assignments in this office; and that the said Letters Patent should be read with this correction therein that the same may conform to the record of the case in the Patent Office.

Signed and sealed this 5th day of August, A. D., 1919.

[SEAL.]

R. F. WHITEHEAD,

Acting Commissioner of Patents.

Cl. 217—66.
